(57) **CLAIM**

The ornamental design for a gauge for measuring, as shown and described.

DESCRIPTION

FIG. 1 is a perspective view of the gauge for measuring; FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof;

FIG. 8 is another perspective view showing the gauge for measuring in an environmental subject matter thereof; and, FIG. 9 is another perspective view showing the gauge for measuring in an environmental subject matter.

The broken lines in the drawings depict environmental subject matter for the gauge for measuring only and form no part of the claimed design.
